UNITED STATES PATENT OFFICE

110,358

DESIGN FOR AN AUTOMOBILE BODY

Trenor P. Judd, Cairo, Ill.

Application November 6, 1937, Serial No. 72,661

Term of patent 7 years

To all whom it may concern:

Be it known that I, Trenor P. Judd, a citizen of the United States, residing at Cairo, in the county of Alexander and State of Illinois, have invented a new, original, and ornamental Design for Automobile Bodies, of which the following is a specification, reference being had to the accompanying drawing forming a part thereof.

Fig. 1 is a side elevational view of an automobile body, showing my new design.

Fig. 2 is a plan view of the design shown in Fig. 1, and

Fig. 3 is a view showing in front end elevation the design illustrated in Fig. 1.

I claim:

The ornamental design for an automobile body substantially as shown.

TRENOR P. JUDD.
